MACHINE FOR ASSEMBLING IDLER
ROLLERS

Otto P. Haegele, Columbus, Ohio, assignor to Joy
Manufacturing Company, a corporation of
Pennsylvania

Original application July 1, 1947, Serial No.
758,416, now Patent No. 2,655,718, dated Octo-
ber 20, 1953. Divided and this application De-
cember 20, 1950, Serial No. 201,799

4 Claims. (Cl. 153—21)

1

This invention relates to an idler roller assembly machine and more particularly to a machine for assembling parts of a belt idler roller especially designed for use with endless belt conveyors.

It is an object of the present invention to provide an improved belt idler assembly machine. Another object is to provide an improved machine for assembling parts of an idler roller and for securing certain of the parts in assembled position. Another object is to provide an improved means for crimping or indenting the ends of the idler rollers to hold the end shaft supports or end sleeves securely in position within the roller members. A still further object is to provide an improved belt idler assembly machine having improved adjustable means whereby rollers of different diameters and of different lengths may be assembled within the machine. These and other objects and advantages of the invention will, however, hereinafter more fully appear.

The present application is a division of my co-pending application, Serial No. 758,416, filed July 1, 1947, now matured into Patent No. 2,655,718, granted October 20, 1953.

In the accompanying drawings there is shown for purposes of illustration one form which the invention may assume in practice.

In these drawings:

Fig. 1 is an enlarged, fragmentary, perspective of the front portion of an idler assembly machine showing features of the invention.

Fig. 2 is a horizontal sectional view showing the fluid cylinders and associated mechanism for crimping or indenting the roller members to secure the end shaft supports in place.

Fig. 3 is a longitudinal vertical sectional view taken substantially on line 3—3 of Fig. 2.

Fig. 4 is a diagrammatic view illustrating the hydraulic fluid system.

In this illustrative construction, as shown in the drawings, the improved belt idler assembly machine comprises a framework 1 by which are carried fluid cylinders and associated mechanism 2 for crimping or indenting the roller members to secure the end shaft supports securely in place therein. Each idler roller includes a roller shaft 3, an outer tubular roller member 4 and cuplike end shaft supports or end sleeves 5 which are inserted within the tubular roller member to hold the shaft centrally in position and the roller is first partially assembled within the machine in the manner fully disclosed in the co-pending application Serial No. 758,416. The par-

tially assembled roller may be placed on curved seats 6 of spaced vertical blocks 7 of the crimping mechanism 2, the blocks being secured, as by screws, to vertical frame portions 8 on the frame 1 (Figs. 2 and 3). In Fig. 1 the roller is shown in seated position; and when the roller is placed in such position, its left hand end sleeve 5, as viewed in Fig. 2, is placed over a cylindrical portion 9 of a support 10, the latter being secured, as by screws, to an adjustable plate 11. This plate is guided for horizontal adjustment on an adjustable part of the frame, as later described, and is provided with an adjusting screw 12. At the right hand end of the roller, as viewed in Fig. 2, is a horizontal transverse guideway 13 extending lengthwise of the roller and in which a sliding cross head 14 is guided for horizontal movement, and this cross head is secured to a piston rod 15 of a reciprocable piston 16 contained in a horizontal fluid cylinder 17, the latter being suitably secured to a horizontal frame portion 18 of the frame 1. Guided at 19 for transverse adjustment, as by adjusting screws, on the cross head, is a vertical plate 20 carrying a member 21 provided with a cylindrical portion 22 adapted to fit within the right hand end sleeve 5 of the roller, as viewed in Fig. 2, when the piston 16 is moved toward the left, under the influence of pressure fluid, to bring the cross head 14 into the position shown. In Fig. 1, the cross head and crimping tools are shown in retracted position. Thus, when the cylindrical portions 9 and 22 of the members 21 and 10 are positioned within the end sleeves 5 of the rollers, as shown in Fig. 2, the roller is firmly maintained in position, ready for crimping. Arranged longitudinally of the framework at substantially right angles to the longitudinal axis of the roller are horizontal fluid cylinders 25, 25, arranged in parallel relation and containing reciprocable pistons 26 (see also Fig. 3) having horizontal piston rods 27. These cylinders are secured to vertical frame portions 28 parallel to the frame portions 8, and the upper ends of the right hand frame portions, as viewed in Fig. 1, are held rigidly in spaced relation as by a bolt 29 and nuts 30, as shown. Threadedly secured at 31 to the outer ends of the piston rods are tool holders 32 guided in horizontal guideways 33 in blocks 34 rigidly secured, as by screws, to adjacent portions 35 mounted on the framework. The adjustable plate 11 (Fig. 2) is guided on the left hand frame portion 35 which is laterally adjustable, as later explained. Adjustable stops 36, threaded on the bodies of the tool holders, engage the outer surfaces of

the guide blocks 34 for limiting the rectilinear inward movement of the tool holders. Lock washers suitably hold the adjustable parts in position, as shown. Attached at 37 to the inner ends of the tool holders are crimping or indenting tools 38. When the pistons 26 are moved outwardly under the influence of pressure fluid, the tools 38 are pressed inwardly against the outer surface of the roller 4 to crimp or indent the latter, as at 39 (Fig. 2), to secure firmly the end shaft supports 5 within the end of the bore of the roller member 4. By proper adjustment of the plates 11 and 20 and by interchanging the seat-providing blocks 7 with different size blocks and interchanging the support members 10 and 21 with different size ones, rollers of different diameters may be supported in crimping position and crimped in an obvious manner. When the work holders and cross head are retracted, as shown in Fig. 1, a partially assembled roller may be removed from the seats 6 on the blocks 7 and placed on an inclined conveyor 40 (Fig. 1), where it may roll by gravity downwardly toward the back of the machine, in the manner fully disclosed in the above mentioned copending application.

In order to accommodate rollers of different lengths than those shown, the left hand lower frame 35 (Fig. 2), supporting the left hand crimping cylinder 25 and the roller support member 10, is slideable transversely along horizontal guideways 41 on a transverse bed frame 42, likewise secured to the framework, and suitable bolts 43 are likewise provided to secure the frame in adjusted position. Thus, rollers of different lengths, as well as rollers of different diameters, may be assembled within the machine. It will be noted that the roller conveyor 40 is made of sufficient width to accommodate the rollers of greatest length.

Now referring to the hydraulic fluid system, as shown diagrammatically in Fig. 4, it will be noted that a conventional motor driven pump 45 has its intake connected by a conduit 46 to a tank 47 adapted to contain a fluid, preferably a liquid such as a light lubricating oil. The pump discharge is connected by conduit 48 to the supply passage of a valve box 49 of a conventional control valve mechanism 50, herein mounted on the framework at the front end of the machine in the manner clearly shown in Fig. 1. The valve block has a horizontal bore containing a conventional slide valve 51, preferably of the balanced spool type, and having an operating lever 52. The bore containing this slide valve is connected by conduits 53 and 54 to the opposite ends of the roller holding cylinder 17, and branch conduits 55 and 56 lead from the conduits 53 and 54 respectively, to the opposite ends of the crimping cylinders 25. Conduit 56 is connected to the conduit 54 through a conventional spring loaded valve 57 which remains closed, cutting off communication of the conduit 56 with the conduit 54 until the piston in the cylinder 17 has moved its full distance. When the pressure builds up in the cylinder 17 due to cessation of piston movement, the valve 57 automatically opens, admitting fluid under pressure through conduit 56 to the cylinders 25, thereby to move the pistons therein toward crimping position. It will thus be seen that the cylinder 17 is first operated firmly to hold the roller in crimping position and thereafter, in a definite sequence, the cylinders 25 are operated to effect crimping. The conduit 56 is connected through

5 a conduit 58 controlled by a check valve 59 to the conduit 54 so that when the latter is vented, fluid may flow from the cylinders 25 through conduit 58, past the check valve 59 to the conduit 54, wholly independently of the valve 57 which is, at that time, closed. Fluid may flow to the conduit 56 only past the relief valve 57. The discharge passage of the valve box 49 is connected by a conduit 60 back to the tank 47. The valve box 10 contains another control valve for other fluid operated devices of the machine as is fully disclosed in the above mentioned copending application, but since this additional valve does not enter into the present invention it is not described in detail herein.

15 As a result of this invention an improved belt idler assembly machine is provided whereby assembly of idler parts may be quickly and easily accomplished, with a minimum of time and expense. It will further be evident that by the provision of the fluid operated devices for holding and crimping the idler rollers the assembling operation is greatly facilitated. By the provision of the automatic control for the crimping mechanism the roller is always firmly held in position prior to the crimping operation, in a definite sequence. By the provision of the adjustable and interchangeable roller supporting and centering structures, rollers of different diameters and of different lengths may be assembled within the machine. Other uses and advantages of the invention will be clearly apparent to those skilled in the art.

20 30 35 40 While there is in this application specifically described one form which the invention may assume in practice, it will be understood that this form of the same is shown for purposes of illustration and that the invention may be modified and embodied in various other forms without departing from its spirit or the scope of the appended claims.

45 What I claim as new and desire to secure by Letters Patent is:

1. In a machine for assembling rollers, supports for a horizontal roller, means for mounting one of said supports for adjustment relative to the other thereby to accommodate rollers of different lengths, a power operated device aligned with the roller on said supports for firmly holding the roller in a stationary horizontal position, power operated devices arranged in parallel relation at right angles to the roller near the opposite ends thereof for peripherally crimping or indenting the roller concurrently at its ends to secure parts firmly in assembled relation therewith, and means for mounting one of said parallel power operated devices for adjustment with said adjustable support to vary their distance apart thereby to enable crimping or indenting of the rollers of different lengths.

2. In an idler assembly machine, a support for receiving an idler member for supporting the latter in a horizontal position, a power operated device acting endwise on the idler member for holding the latter firmly in a stationary horizontal position on said support, power operated devices arranged in right angular relation with respect to the axial line of said first mentioned power operated device and acting transversely of the horizontal idler member near the ends of the latter for peripherally crimping or indenting the idler member concurrently at longitudinally spaced points to secure parts in position with respect thereto during assembly, and automatic control means associated with said power op-

erated means and embodying a control element responsive to the power conditions within said first mentioned power operated device for automatically effecting, in a definite sequence, operation of said power operated crimping devices only after the idler member is firmly held in horizontal position on said support.

3. In an idler assembly machine, a support for receiving an idler member for supporting the idler in a horizontal position, a power operated device aligned with said idler member at one end of said support and acting endwise on the idler for holding the latter firmly in its horizontal position on said support, power operated devices, one arranged near each end of the idler member on said support with their axes extending in parallelism at right angles to the axial line of said first mentioned power operated device for peripherally crimping or indenting the idler member concurrently at longitudinally spaced points to secure parts in position with respect thereto during assembly, and mounting means for said last mentioned power operated devices including a horizontal, longitudinally extending guideway for one of said latter devices and along which said latter device is adjustable to vary the distance apart of said latter power operated devices to enable peripheral crimping or indenting of rollers of different lengths.

4. In an idler assembly machine, a support for receiving an idler member for supporting the idler

5 in a horizontal position, a power operated device aligned with said idler member at one end of said support and acting endwise on the idler for holding the latter firmly in its horizontal position on said support, power operated devices, one arranged near each end of the idler member on said support with their axes extending in parallelism at right angles to the axial line of said first mentioned power operated device for peripherally crimping or indenting the idler member concurrently at longitudinally spaced points to secure parts in position with respect thereto during assembly, said support for the idler member providing longitudinally spaced seats for interchangeably receiving different size supporting elements for receiving and supporting the ends of idler members of different diameters.
